UNITED STATES PATENT OFFICE.

GUSTAV OTTO WOLTERS, OF VILLIGST, NEAR SCHWERTE, GERMANY.

REGENERATIVE COKE OVEN.

Application filed September 10, 1926, Serial No. 134,613, and in Germany March 14, 1925.

My invention relates to improvements in coke ovens, and more particularly in ovens of the class in which the coking chambers are comparatively high and the air for supporting combustion is supplied at different points of the length of the heating passages. The object of the improvements is to provide an oven of this type in which the main portion of the air for supporting combustion is preheated within the regenerators and delivered into the heating passages of the oven at the inlet end thereof, the direction of the flow of the air coming from the regenerators being changed whenever the flow of the heating gases to the heating passages is reversed, while additional air is supplied to a median part or median parts of the heating passages. This additional air is preheated in separate chambers in which the direction of its flow remains the same even when reversing the flow of the gases through the heating passages, the said additional air being preferably conducted through passages or pipes or chambers provided in the walls of the regenerators or within the regenerators themselves, where it is heated at high temperature. Thus, the said passages or pipes or chambers work in the same way as recuperators. By heating the coke oven, the heat is uniformly distributed all over the length of the heating passages.

For the purpose of explaining the invention two examples embodying the same have been shown in the accompanying drawings, in which the same reference characters have been used in all the views to indicate corresponding parts.

In said drawings,

Fig. 1, is a partial sectional elevation showing the coke oven and the regenerators,

Fig. 2, is a sectional elevation taken on the line 2—2 of Fig. 1,

Fig. 3, is a sectional elevation similar to the one shown in Fig. 1 and illustrating a modification,

Fig. 4, is a sectional elevation taken on the line 4—4 of Fig. 3, and

Fig. 5, is a sectional plan view taken on the line 5—5 of Fig. 4.

In the embodiment of the invention shown in Figures 1 and 2 the coke oven is constructed of brickwork and comprises coking chambers *e* horizontally elongated and having heating chambers *F* at opposite sides thereof, said coking and heating chambers being arranged in the upper portion of the brickwork

with the separating or intermediate walls common to both chambers. The heating chambers are divided into alternate pairs of flues *f* and *f'* by vertical partitions *k*, *k'* extending transversely of and upward from the bottom of the heating chambers to adjacent the top thereof with the flues in communication with each other over the tops of the partitions. Regenerators *g*, *g'* are arranged below the coking chambers in parallel relation thereto and each other, said regenerators having connection through passages *i*, *i'* with passages *h*, *h'* which latter passages are adapted for connection with a source of air supply for supporting and stimulating combustion in the heating chambers, or to means for exhausting the products of combustion from the regenerators. To pass preheated air to the lower portions of the flues *f*, *f'* of the heating chambers from the regenerators *g*, *g'* and for conducting the burned gases or the products of combustion from said chambers to the regenerators passages *b*, *b'* are provided to connect the regenerators with the flues, the passages *b* communicating with the regenerators *g* and the flues *f* while the passages *b'* communicate with the regenerators *g'* and flues *f'*. Passages *j*, *j'* leading from a source of gas supply are arranged in the wall of the oven in interposed relation to the heating chambers and regenerators and have burners *a*, *a'* connected thereto opening into the respective flues *f*, *f'* of the heating chambers. Coking ovens constructed in accordance with the foregoing description and the operation thereof are well known to those skilled in the art.

The partition walls *k'* alternating with the partition walls *k*, and separating the heating chambers into flues are arranged with passages *c* extending longitudinally therethrough, and said passages leading through the partition walls *o* of the regenerators from chambers *m* extending through the walls of the regenerators and parallel thereto. The passages *c* open into the upper portion of the heating chambers *F* through the tops or the sides adjacent the tops of the partitions. The chambers *m* communicate with an air supply and the air as it passes therethrough and the passages *c* is preheated before it enters into the heating chambers by the heat transmitted through the walls of the regenerators.

In the operation of the oven air and gas are supplied, for instance, through the passages *b* from the regenerators *g* and burners *a*

to the bottom portion of the flues f of the heating chambers, the air mixing with and serving as a stimulant and aid to the combustion of the gas, and the burning mixture rising in said chambers and passing over the tops of the partitions h' and descending into the flues f' and exhausted through the passages b' to the regenerators g' , which at the time are serving as exhaust flues for the products of combustion, which are exhausted through the passages i' , h' connected with said regenerators g' , the direction of flow of the gases and the exhaust of the products of combustion being that indicated by the arrows. As the gases in the flues f reach the upper ends of the flues additional air is supplied to the partly burnt gases through the passages c to serve as a stimulant to the burning gas and assuring complete combustion of the same. The air admitted through the passages h is previously heated in the passage through the regenerators g , and the additional or secondary air delivered through the passages c is preheated by the heat transmitted through the walls of the regenerators. As is usual in coking ovens of this character, after the regenerators g have been in operation for a certain period of time the regenerators g' are utilized as regenerators and the regenerators g as exhaust passages for the products of combustion. When the direction of flow of the burning gases through the flues f , f' is reversed primary combustion is taking place in the flues f' by supplying the gas thereto through the burners a^1 , and the air for supporting combustion is through passages b^1 connected with the regenerators g^1 , which have before been heated by the waste gases. However, the flow of the additional or secondary air through the passages c is not reversed so that additional air is supplied to the partly burnt gases in the manner hereinbefore described. The burnt gases are exhausted through the passages b , the regenerators g , and the passages i , h .

In Figs. 3 to 5 I have shown a modification in which the fuel and air for supporting combustion are supplied to a series of adjacent vertical passages or flues f^2 in the heating chamber and delivered from said series of flues to a successive series of adjacent passages or flues f^3 , the heating chamber being above and parallel with the two generators g^2 , g^3 which are arranged in endwise relation. As shown the passages a^2 and b^2 open into a series of adjacent vertical passages or flues f^2 , while the passages a^3 and b^3 open into a successive series of adjacent flues f^3 . The passages b^2 communicate with the regenerators g^2 , and the passages b^3 with the regenerators g^3 . Otherwise the construction of the oven is similar to that described with reference to Figs. 1 and 2. In the operation of the oven gas is supplied to the heating passages or flues f^2 of the heating chamber through the passages a^2 , whilst air for supporting combustion of said

gas is supplied through the regenerators g^2 and the passages b^2 . In ascending within the heating passages or flues f^2 the gas is partly burnt. The partly burnt fuel receives an additional supply of air through the passages c , whereupon combustion is completed within the passages f^3 in which the gases descend, the direction of flow of the gases and of the primary and secondary air being that indicated by the arrows. The burnt gases are discharged through the passages b^3 and the regenerators g^3 . After an interval of time the foregoing described flow of the burning gases is reversed, the air for supporting combustion being supplied through the heated regenerators g^3 and the passages b^3 into the passages or flues f^2 , in which it ascends together with the fuel supplied through the passages a^3 . The partly burnt fuel receives a secondary supply of air through the passages c , so that combustion is completed within the passages f^2 . In this instance the burnt gases are used for heating the regenerators g^2 . It will be understood that any suitable number of adjacent passages f^2 and f^3 may be combined in the manner indicated, and that my invention is not limited to the construction shown in Figs. 3 to 5 in which the heating chambers are each divided into two sets of heating passages f^2 and f^3 . In some cases I combine all the passages of the heating chambers, the air ascending in all of said passages and descending in the passages of the adjacent heating chamber.

When using poor gas I provide regenerators for air and gas, and in the case, instead of supplying additional air I can supply additional poor gas preheated in recuperators similar to those used for preheating the additional air.

I claim:

1. In a coke oven, a horizontally elongated coking chamber, heating chambers juxtaposed to the opposite sides of the coking chamber arranged with partitions extending transversely to said coking chamber and upward from the bottom to adjacent the top of each of the heating chambers separating each of said chambers into flues communicating with each other at the tops of the partitions, regenerators arranged below and parallel to the coking chamber, fuel inlets to the bottoms of the flues, primary air passages connecting the regenerators with the bottoms of the flues for supplying air from said regenerators to the heating chambers for supporting combustion of fuel therein and arranged with means for controlling flow of air through the regenerators to the heating chambers and flow of products of combustion from the heating chambers through said passages, and secondary air inlet passages connected with a source of air supply and extending vertically through the walls between the regenerators and through alternate partitions in each of the heating chambers and having outlets from

the tops of said alternate partitions into the heating chambers for delivering a secondary air supply to the heating chambers at a point remote from the bottoms of said flues.

heating chambers being in communication with one regenerator, and the series of successive flues in the other half of the same heating chamber communicating with another regenerator. 10

5. 2. A coke oven as claimed in claim 1, wherein two regenerators are arranged end to end below the coking chamber, the successive series of flues in one half of one of said

In testimony whereof I have affixed my signature.

GUSTAV OTTO WOLTERS.
